STEP FORM

Filed Aug. 6, 1928

UNITED STATES PATENT OFFICE

GEORGE H. MILLER, OF MILWAUKEE, WISCONSIN, ASSIGNOR TO METAL FORMS CORPORATION, OF MILWAUKEE, WISCONSIN

STEP FORM

Application filed August 6, 1928. Serial No. 297,828.

This invention is directed to a novel construction of a so-called step form, commonly availed of in concrete construction enterprises. As the name implies, a step form is utilized to mold or form concrete in a molten state until it has set, and is used to fashion the concrete into a stepped configuration. The conventional type of step forms now commonly employed comprise, mainly, side 10 pieces or members which are formed with angular cut-aways or recesses, together with suitable means for positioning the said side pieces, and so-called longitudinal form members or risers which are affixed to the side 15 pieces in the angular cut-aways or steps thereof, so that the said riser form members assume a vertical position which is a prime requisite of the proper functioning of the entire form. It is readily appreciable that a 20 form of the type heretofore used is capable of utilization in only one relative angular position; that is, in order for the riser form members to be vertical, it is essential that the side pieces assume a certain definite 25 angle of inclination. Needless to say, this condition limits to a great extent the range of usage of any step form.

With the foregoing in mind, the primal object in view is the provision of a step form 30 of the character described, which is capable of adjustment into various angular inclinations while in operative position. More specifically, it is an object to provide a step form of this type which includes instrumentalities for varying the angular relation between the riser form members and the side 35 pieces. This feature permits the side pieces to be placed in any position within a certain range and still impart to the riser forms the 40 property of verticalness which is so essential to their proper functioning.

In carrying out my idea into practical use, I employ flanged plates which are pivoted to the side pieces adjacent to the cut-aways. 45 Bolt and slot arrangements are also provided for holding the plates in any of their adjusted positions. The plates are so arranged that one of their vertical edges is adapted to have the riser forms bear there-against, 50 and the flange on the plate constitutes a

means by which the riser form members are clamped or held in position.

It is a noteworthy object of the invention to provide adjusting devices as hereinbefore described, which are capable of being used 55 in conjunction with clamping devices now conventionally in use, such as the clamping device illustrated and described in the patent to Trester No. 1,549,632. This feature is manifest in the presence of the flanged 60 plate. The flange acting as anchorage means for the hook on the clamping device.

Various other more detailed objects and advantages will in part become apparent and in part be hereinafter stated as the description 65 of the invention proceeds.

For a full and more complete understanding of the invention, reference may be had to the following description and accompanying drawings, in which, 70

Figure 1 is a view in perspective of a step form including features provided by this invention.

Figure 2 is a side view, somewhat fragmentary, of one of the side pieces bringing 75 out the flanged plates thereon.

Figure 3 is a fragmentary detail showing of the slot and bolt arrangement associated with one of the flanged plates for holding it 80 in its adjusted position.

Figure 4 is a detail cross sectional view taken about on the line 3—3 of Figure 2, and

Figures 5 and 6 are views bringing out the construction of one of the clamping devices. 85

While a preferred specific embodiment of the invention is herein set forth, it is to be understood that I am not to be limited to the exact construction illustrated and described because various modifications of 90 these details may be provided in putting the invention into practice within the purview of the appended claims.

Throughout the various figures of the drawings and the specification, like reference characters denote corresponding parts. 95

A step form of the character described comprises generally, side pieces A, riser forms B, and means of anchorage for the form referred to generally by the refer- 100

ence character C. In the present instance, the anchorage means C comprises stakes 1, which pass through openings in brackets 2, carried by the side pieces A.

5 The side pieces A are cut away as shown at 3 to provide angular shaped recesses so as to accommodate the riser form members B in vertical positions.

Referring now to Figure 2, each of the 10 side pieces A carries plates 4 preferably on its outer side, said plates 4 having turned over flanges on the edges thereof as shown at 5, which impart to the plate the property of rigidity and also serve a purpose to be 15 hereinafter set forth. There is one of these plates located adjacent to the edge of the cut-aways 3, and the plates are so arranged with respect to their pivotal mounting at 6 that one flanged edge thereof extends substantially in alignment with the vertical 20 edge of the cut-aways 3. However, the relation of the edge of the plate 4 with the edge of the cut-away 3 may be varied, due to the pivotal mounting at 6. Located diagonally 25 opposite with respect to the pivot 6, the plate 4 is provided with a slot 7 through which projects a threaded bolt carried by the side piece A. Some suitable form of clamping means such as wing nut 8 is threaded 30 on the bolt and is adapted to bear against the plate 4 to positively hold the same in position. It is obvious that the plate 4 may be adjusted by means of the bolt and wing nut 8 and slot 7 so that its upwardly 35 extending edge will be in a vertical plane.

The riser forms B may be held clamped against the flanged edges 5 of the plates 4 by any preferred clamping medium although in the present instance, I have shown the 40 type of clamping device shown in the patent to Trester hereinbefore identified, inasmuch as said clamping device has a hook member 9 which is particularly adapted for cooperation with the flange 5 on plate 4.

45 In assembling the form, side pieces A are anchored and the plates 4 put in proper position with vertically extending edges by means of the bolt and slot arrangement 7 and 8. The riser forms B are now clamped 50 to the plates by passing the hook members 9 of the clamping device through proper openings in the form. These openings are preferably equidistantly spaced along the form members so that the step form may 55 have varied dimensions. These openings are designated 10. Upon insertion of the hook member through the opening 10 so that it engages with flange 5, the cam portions 11 of the clamping device are brought into engagement 60 with the form and due to the cam construction, the rigid clamping effect is obtained.

Having thus described my invention, what I claim as new and desire to secure by Letters Patent of the United States is:—

1. A step form of the class described, comprising, in combination, side form members having angular cut-away recesses with substantially vertically extending edges, plates pivotally mounted on the side members having edges adjacent to and in substantial alignment with the vertically extending edges of the side forms, means for holding the plates in adjusted position, longitudinal vertically extending form members and cammed clamping devices having parts adapted for interlocking with the plates for holding the longitudinal form members against the vertically extending edges of the plates. 70

2. A step form of the class described, comprising, in combination, side form members having cut-aways therein defining substantially vertically disposed edges on the side form members, plates carried by the 85 side form members, each plate having one edge substantially adjacent to one of the vertically disposed edges of the side form members, and means for adjusting the relative position of the plates with respect to 90 the side form members so that vertical edges of the plates may be adjusted with respect to the vertical edges of the side form members and thereby made to assume a true vertical position, regardless of the position of 95 the edges of the side form members.

In testimony whereof I affix my signature.
GEORGE H. MILLER.
